UNITED STATES PATENT OFFICE.

MORGAN K. ARMSTRONG, OF WINNETKA, ILLINOIS, ASSIGNOR TO BESTWALL MANUFACTURING COMPANY, OF CHICAGO, ILLINOIS, A CORPORATION OF DELAWARE.

PLASTER-BOARD.

1,278,821.

Specification of Letters Patent. Patented Sept. 17, 1918.

Application filed January 4, 1918. Serial No. 210,290.

To all whom it may concern:

Be it known that I, MORGAN K. ARMSTRONG, a citizen of the United States, and a resident of Winnetka, in the county of 5 Cook and State of Illinois, have invented certain new and useful Improvements in Plaster-Board; and I do hereby declare that the following is a full, clear, and exact description thereof, reference being had to 10 the accompanying drawings, and to the letters of reference marked thereon, which form a part of this specification.

This invention relates to improvements in plaster board and consists of the matters 15 hereinafter described and more particularly pointed out in the appended claims.

The object of the invention is to provide a plaster board in which the paper is thoroughly adhered or attached to the plastic 20 body and at the same time presents an outer, sized surface so that the board may be handled easily and without damage or waste during the final steps of setting the plaster and drying the board, and also so that the 25 finished board, when used, requires no coat of sizing—as in the case of a plaster wall—to prepare its exposed surface for decoration purposes.

The advantages of my improved plaster 30 board will be made apparent as I proceed with my specification.

In the drawings:

Figure 1 represents in perspective, a fragment of plaster board embodying my invention.

Fig. 2 represents on an enlarged scale, a section through said plaster board.

Plaster board is made in a continuous length upon a cylinder machine wherein a 40 continuous sheet of paper is fed upon a conveyer belt or table toward a pair of horizontally disposed, vertically spaced rolls,—the distance separating the rolls being equal to the intended thickness of the plaster 45 board. As the paper sheet advances toward these rolls, a wet plastic mixture is dumped upon and spread over this sheet of paper, said sheet being the bottom covering for the finished board. A second or top sheet 50 of paper is fed about the top roll and is brought into engagement with the top surface of the wet plastic material already on the bottom sheet, and the two strips of paper with the plastic material between them 55 are passed between the aforesaid rolls, thus

forming the board. The continuous length of board is fed from the rolls over a long table, and during its passage over this the plaster sets. At the end of the table it is cut into certain lengths and is placed upon edge 60 upon trucks, which are removed to a drying room for the purpose of drying out the moisture.

I have found that in the manufacture of plaster board, as thus briefly described, if 65 the paper covering sheets are not sized, they will adhere securely to the plastic body material of the board. However, such unsized paper absorbs such quantities of moisture from the wet plastic material as to become 70 substantially saturated. The board, as it comes from the machine, is in a limp, soggy condition, which makes it almost impossible to subject it to the handling required in the final drying steps of the process. On the 75 other hand, a paper which has been thoroughly treated throughout with a suitable sizing solution, is objectionable. While the saturation of the unsized paper is eliminated and the board, after setting, is for that 80 reason in better condition for handling, the sized paper has the defect that it does not and cannot be made to adhere to the plastic body of the board, and when said body is thoroughly dried, separation of the paper 85 from the plastic body occurs and bulges or large blisters appear in the covering. In my improved board, the objectionable features of both sized and of unsized paper are eliminated.

The improved plaster board comprises top and bottom covering sheets 5 and 6, of paper, and an intermediate body or layer 7 of plastic composition, to which the paper adheres. Each covering sheet is made up 90 of a plurality of plies, in this case five, namely: 8, 9, 10, 11 and 12 respectively. The outermost plies 8, 9 and 10 of each covering sheet are thoroughly sized during their manufacture. The inner plies 11 and 12 are unsized. To insure the fact that there will be no sizing whatever in the plies 11 and 12, and to insure uniformity throughout the entire paper supply roll, the paper during its manufacture is "slack-sized", as 105 the process is called in the trade, to neutralize any sizing which may exist in the stock from which these plies are made.

By using paper which has the outer plies sized and the inner plies unsized, I obtain 110

a covering for a plaster board, which has not only the adhesive capacity of an unsized paper, but the stiffening and strength and other desirable qualities of a sized paper.

5 A plaster board having top and bottom coverings of the kind above described, can be readily handled immediately as it comes from the table without damage, can be 10 placed on edge on trucks and can be put in racks or hangers to be dried without damage.

As the sizing is limited to the outer plies of the covering sheet, the sizing may be as 15 thoroughly applied as necessary, so that when the plaster board is used and placed to cover a wall, no additional sizing is required to prepare its exposed surface for 20 decorating. Thus the cost of sizing required in the case of an ordinary plaster wall, is saved.

In illustrating and describing the covering sheets, I have referred to a sheet composed of five plies, three of which are thoroughly sized and two of which are unsized or slack sized. From the foregoing description, however, it will be understood that the covering sheets may either or both be of any number of plies, dependent upon the 25 weight of paper required to make the board to meet the demands of any particular situation,—it being only necessary in carrying out the invention, that the ply or plies providing the exposed surfaces of the board, be 30

sized, and that the ply or plies next adjacent to the plastic body, be unsized or slack sized, so that they will adhere permanently to the plastic body, not only during the process of manufacturing the board, but also after the board has been thoroughly dried 40 out and made ready for the market.

I claim as my invention:

1. A board comprising a body made of plastic material and top and bottom covering sheets of paper, said top and bottom covering sheets each consisting of a plurality of plies, the plies of said paper covering nearest to the plastic body being unsized and adapted to adhere to the adjacent surface of said plastic body, and the outer 50 plies of said paper covering being sized.

2. A board comprising a plastic body and top and bottom covering sheets of paper, each covering sheet consisting of a plurality of plies, the plies of said covering sheet near said plastic body being slack sized and adapted to adhere permanently to said plastic body, and the plies remote from said plastic body and providing the outer surface of the board, being thoroughly sized. 55

In testimony that I claim the foregoing as my invention, I affix my signature in the presence of two witnesses, this 19th day of December, A. D. 1917.

MORGAN K. ARMSTRONG.
